CHUSETTS, A CORPORATION OF MASSACHUSETTS

MACHINE FOR FORMING YARN PACKAGES

Application filed September 21, 1928. Serial No. 307,365.

Our invention relates to a machine for winding yarns, or other filamentary material, into independent packages of such size that the yarn may later be conveniently wound on bobbins or filling carriers, or the packages may be used as desired, to make up a warp for weaving.

In Patent No. 1,503,381, issued July 29, 1924, to Arthur L. Remington, there is shown and described a machine for forming independent yarn packages that is characterized by the provision of a vertically movable roll which is adapted to compress the yarn in the various packages as it is wound and to also maintain each yarn in the position in which it is laid by the movement of a traversing member. In the above described patented arrangement, the whole traversing mechanism is supported by the pressure roll and therefore moves vertically as the yarn packages increase in diameter beneath the pressure roll, and it is one of the objects of the present invention to provide an improved package forming machine in which the necessity for permitting vertical movement of the traversing mechanism with its associated binding roll is eliminated.

According to the present invention we provide an improved arrangement in which the separate yarns are led to the package carrying shaft by a traversing mechanism which is adapted for a reciprocatory movement only, and is not capable of vertical movement with respect to the package shaft. Furthermore, the separate yarns are led around a rotatably driven friction roll on which the package forming shaft bears, so that this roll serves the double function of driving the package shaft to wind the packages and of providing sufficient pressure between each package and the roll to maintain the yarn in the position in which it is laid by movement of the traversing mechanism. As a result, our improved machine is much simpler in construction and more convenient to operate than machines of the type shown in the aforesaid Patent No. 1,503,381. Additional advantageous features of our invention will hereinafter more fully appear from the following detailed description, taken in connec-

tion with the accompanying drawings in which:—

Fig. 1 is a view in side elevation of a portion of a package forming machine embodying our invention, some parts being shown in section.

Fig. 2 is a plan view of a portion of the parts shown in Fig. 1.

Fig. 3 is a fragmentary perspective view showing some of the parts of Fig. 2 removed from the machine.

Fig. 4 is a fragmentary sectional view showing a detail of construction.

Like reference characters refer to like parts throughout the drawings.

Referring to Fig. 1, the machine comprises a frame 1 providing inclined side members 2 between which are supported a number of package forming mechanisms identical in construction, so that only one need be described in detail. Yarn 3 for forming the packages is led from a suitable source such as a creel, not shown, to the front of the machine where it passes over a roll 4 carried between vertical extensions 1a of the frame 1 and then downwardly around a second roll 5. The yarn 3 is then led upwardly and is divided between a number of guide rolls 6 corresponding in number to the number of package forming mechanisms, one of which will next be described.

The side frames 2 carry a number of pairs of vertically aligned standards 7, each pair of standards 7 providing oppositely disposed vertical slots 8. A package forming shaft 9 is provided at its ends with reduced portions 10 which are received in a pair of slots 8, so that the shaft 9 is adapted to move freely in a vertical plane between a pair of standards 7. As shown at the right in Fig. 1, the shaft 9 when empty is adapted to rest in engagement with the periphery of a roll 11 having a frictional surface, the ends of which are received in bearing blocks 12 also slidably within the slots 8. The end portions of the shaft 11 adjacent the bearing blocks 12 bear on a pair of friction discs 13 mounted on a shaft 14 extending between the side frames 2 and journaled therein. As best shown in Fig. 2 the shaft 14 extends beyond the side

frames 2 and carries at one end a bevel gear 15 in mesh with a bevel gear 16 carried on a shaft 17 extending the length of the machine. The shaft 17 is in turn driven from 5 a cross shaft 18 through gearing 19, the cross shaft 18 being journaled below the frame extension 1a and carrying a pulley 20 by means of which the shaft 18 may be driven from a suitable source of power, not shown.

10 When the shaft 17 is driven as described above, all of the shafts 14 are driven in unison and each pair of friction discs 13 are adapted to drive the roll 11 in engagement therewith, leaving the roll 11 free between 15 the friction discs 13 combined weight of a package shaft 9 and its associated roll 11 is sufficient to cause the necessary frictional engagement between the surfaces. Rotation of each shaft 14 is also depended upon to 20 drive the traversing mechanism that is employed in connection with each package shaft 9 to deliver the several ends of yarn to the shaft 9 with a traversing movement for the formation of separate packages thereon. To 25 this end, the right-hand end of each shaft 14 carries a spur gear 21 in mesh with a gear 22 mounted on a short shaft 23, the shaft 23 also carrying a traverse cylinder 24, the surface of which provides a spiral groove 25, over 30 which extends a traverse bar 26. As best shown in Fig. 2, the traverse bar 26 is slidably mounted in guides 27 provided by the side frames 2, the end of the bar 26 extending over the surface of the cylinder 24 carrying 35 a roll 28 received in the groove 25. The groove 25 is so formed that one revolution of the shaft 23 is adapted to impart a complete back and forth movement to the traverse bar 26, the amplitude of this movement 40 being dependent upon the pitch of the groove 25. The traverse bar 26 has connected thereto a number of arms 29, each pivoted at 30 and providing a slot 31 for receiving one of several pins 32 carried by the traverse 45 bar 26, so that reciprocatory movement of the bar 26 causes the arms 29 to swing in unison.

As best shown in Fig. 1, each arm 29 provides a thread eye 33 to which an end of yarn 50 is led from one of the guide rolls 6 and after passing through the eye 33 the yarn 3 is led through a notch 34a provided in a finger 34 extending beyond the eye and also carried by the arm 29. Each finger 34 terminates at a 55 point closely adjacent the roll 11 and the notch 34a is so disposed as to deliver the yarn 3 substantially tangent to the under side of the roll 11, the space between the roll 11 and the shaft 14 being free, see Fig. 1. The yarn 60 3 passes upwardly around the roll 11 and then in an opposite direction around the surface of the package shaft 9, the yarn being held between the opposed surfaces of the shaft 9 and roll 11 at the point where the yarn 65 passes on to the shaft 9.

When a shaft 14 is driven as previously described, the friction discs 13 will drive the roll 11 and shaft 9 in unison but in opposite directions, at the same time a set of fingers 34 carried by the traverse bar 26 will deliver 70 several ends of yarn 3 to the shaft 9 with a traversing movement. As a result, the yarn 3 will be wound on the shaft 9 in separate packages, the width of which will be determined by the amplitude of the movement of 75 the traverse bar 26. As an end of yarn 3 is moved back and forth on the roll 11, the pressure exerted between the roll 11 and the shaft 9 at the point where the yarn passes on to the shaft 9, or the package, will serve to maintain 80 the yarn in the position in which it is laid by movement of the traverse bar 26, thereby insuring the formation of compact yarn packages of uniform width and wind. As the yarn packages increase in diameter the 85 shaft 9 is free to move upwardly between the standards 7.

In order to further compact the yarn in the packages, a pressure roll 35 is supported at its ends in bearing blocks 36 freely movable in the slots 8, the roll 35 resting on the yarn packages as they are formed and being adapted to move upwardly between the standards as the yarn packages increase in diameter. After the yarn packages have been 90 completely formed on the shaft 9, the pressure roll 35 may be conveniently raised above the yarn packages, as indicated in Fig. 1, by means of hand wheels 37 provided at the ends of a shaft 38 extending between the standards 7 behind the pressure roll 35. As shown in Fig. 4, the shaft 38 is mounted in brackets 39 extending from the bearing blocks 36 and a pair of pinions 40 are also mounted on the shaft 38 in engagement with teeth 41 provided on the rear face of each standard 7. By turning either one of the hand wheels 37, the roll 35 can be raised on the standards 7 and, if desired, the entire pressure roll assembly can be locked in its raised position 100 by means of pawls 42 adapted to be turned into engagement with the teeth 41. When a pressure roll 35 has been raised and locked in its upper position, as indicated, it is possible to readily remove a shaft 9 with the completed yarn packages thereon by lifting the same until the reduced ends 10 of the shaft 9 come into register with oppositely disposed alined notches 43 provided in the front faces of the standards 7 and opening into the slots 8 in which the ends 10 of the shaft 9 are slidably received.

From the foregoing, it is apparent that by our invention we have provided an improved machine for forming yarn packages, that is particularly characterized by a very simple and effective traversing mechanism. The fact that the yarn delivering fingers 34 are mounted for pivotal movement only, enables the whole traversing mechanism to be dis- 130

posed below the shaft 9 on which the packages are formed. This permits ready inspection of the packages at all times, there being no mechanism whatsoever disposed in the space in front of, or above, the packages being formed. The provision of the roll 11 having the combined function of both frictionally driving the package shaft 9 and holding each yarn end at the point at which it is laid by its traverse finger is also believed to be an improvement over previous machines of this type.

We claim,

1. In a machine of the class described, the combination with a rotatable shaft adapted for vertical movement, a rotatably driven roll supported only at its ends, with its upper surface supporting said shaft, means for conducting yarn around the free under surface of said roll to the surface of said shaft, and means for imparting a traverse to said yarn, whereby the pressure between said shaft and said roll serves to hold the yarn at the point at which it is laid by said traversing means, the upward movement of said shaft as the yarn package wound thereon increases in diameter, being independent of said roll and of said traversing means.

2. In a machine of the class described, the combination with a rotatable shaft adapted for free vertical movement, a roll for supporting said shaft, means cooperating with the end portions of said roll for rotating the same whereby said shaft is frictionally driven by the upper surface of said roll, means for conducting yarn around the free under surface of said roll to the surface of said shaft, and means for imparting a traverse to said yarn, the pressure between said shaft and said roll serving to hold the yarn at the point at which it is laid on the rotating surface of said roll by said traversing means.

3. In a machine of the class described, the combination with a rotatable shaft adapted for free vertical movement, a roll for supporting said shaft, means cooperating with the end portions of said roll for rotating the same whereby said shaft is frictionally driven by the upper surface of said roll, means for conducting yarn around said roll to the surface of said shaft, comprising a pivotally mounted yarn guiding member, and means for imparting an oscillatory movement to said member, whereby yarn is delivered with a traversing movement substantially tangent to the free under side of said roll.

4. In a machine of the class described, the combination with a rotatable shaft adapted for free vertical movement, a roll for supporting said shaft, rotatably driven members for supporting the ends of said roll and frictionally driving said roll and said shaft in unison, with the under side of said roll free, a pivotally mounted yarn guiding member adapted to deliver yarn substantially tangent

to the under side of said roll and around it to said shaft, and means for imparting an oscillatory movement to said yarn guiding member.

5. In a machine of the class described, the combination with a rotatable shaft adapted for free vertical movement, a roll for supporting said shaft, rotatably driven members for supporting the ends of said roll and frictionally driving said roll and said shaft in unison, with the underside of said roll free, a pivotally mounted yarn member adapted to deliver yarn substantially tangent to the under side of said roll and around it to said shaft, and means for imparting an oscillatory movement to said yarn guiding member, the traversing movement of said yarn guiding member being independent of upward movement of said shaft as the package of yarn increases in diameter.

6. In a machine of the class described, the combination with a pair of spaced vertical frame members providing oppositely facing slots, a rotatable shaft mounted at its ends for free vertical movement in said slots, a rotatably driven roll for supporting said shaft and frictionally driving the same, means for conducting yarn around said roll to the surface of said shaft whereby the rotation of said roll causes yarn packages to be wound on said shaft, a pressure roll rotatably supported at its ends in bearing blocks slideable in said frame slots, and means for raising said pressure roll and maintaining it in position above said package shaft to permit the removal of the yarn packages.

7. In a machine of the class described, the combination with a pair of spaced vertical frame members providing oppositely facing slots, a rotatable shaft mounted at its ends for free vertical movement in said slots, a rotatably driven roll for supporting said shaft and frictionally driving the same, means for conducting yarn around said roll to the surface of said shaft whereby the rotation of said roll causes yarn packages to be wound on said shaft, a pressure roll rotatably supported at its ends in bearing blocks slideable in said frame slots, and means cooperating with the bearing blocks for said pressure roll for raising said roll on said frame members and locking the same in position to permit the removal of the ends of the package carrying shaft from said frame slots.
